COLLAPSIBLE HOD

Tyris M. Hevener, Los Angeles, Calif.

Application September 4, 1945, Serial No. 614,241

1 Claim. (Cl. 72—134)

1

This invention relates to a hod so constructed that the same may be collapsed and readily carried or, when not in use, can be stored in a small space.

A still further object is to provide a hod of this character which can be quickly set up for use and which will operate efficiently for holding all kinds of materials, whether solid or semifluid.

A still further object is to provide a hod which is simple and durable in construction and will not readily get out of order.

With the foregoing and other objects in view which will appear as the description proceeds, the invention consists of certain novel details of construction and combinations of parts hereinafter more fully described and pointed out in the claim, it being understood that changes may be made in the construction and arrangement of parts without departing from the spirit of the invention as claimed.

In the accompanying drawings the preferred form of the invention has been shown.

In said drawings—

Figure 1 is a side elevation of the hod set up for use, the handle being broken away.

Figure 2 is an elevation of the back end thereof.

Figure 3 is a top plan view.

Figure 4 is a section on line 4—4, Figure 1.

Figure 5 is a view showing the hod collapsed.

Figure 6 is an enlarged section through a portion of the hod taken on the line 6—6, Figure 2.

Figure 7 is a perspective view of one of the reinforcing frames of the hod.

Referring to the figures by characters of reference, 1 and 2 designate bottom strips which are substantially wedge-shaped in cross-section and formed with depending flanges 3. These strips are so proportioned that when they are pressed together along their inner faces, their top faces 4 will be aligned substantially at right angles to the meeting faces of the strips, with both the inner and top faces meeting along a line drawn longitudinally through the center of the hod. A strip of soft material such as rubber has been indicated at 5 and is seated in opposed grooves 6 within the strips 1 and 2. This strip is removably mounted in one of the grooves but cemented or otherwise secured in the other groove so that when the members are moved apart, the strip will pull out of one of the grooves as shown particularly in Figure 5.

When the strips 1 and 2 are in contact with each other as shown for example in Figures 2 and 4, their outer sides diverge upwardly as indicated at 7 and to each of these diverging sides

2

is firmly secured the bottom portion of one of the side-boards 8 of the hod. Each side-board can be of the usual configuration.

Secured to the inner side of each of the side-boards is a reinforcing frame one of which has been shown in detail in Figure 7. This reinforcing frame comprises a top strip 9 shaped to follow the contour of the top edge of the side-board and also having an end leg 10 and an intermediate leg 11, the end leg being secured to the side-board adjacent to but spaced inwardly from the back edge 12 thereof. The legs 10 and 11 and also the front end of the strip 9 have bottom strips 13 extending laterally therefrom, these strips being fastened to the surface 4 of one of the strips 1 and 2 and the corresponding opposed strips 13 of the two frames being connected by hinges 14 centered above the meeting faces of the strips 1 and 2. As shown in the drawings the frames can be seated in grooves in the side-board and bottom strips provided therefor.

The respective legs 10 and their associated strips 13 extending therefrom are provided along their forward edges with stop flanges 15 extended toward each other, one of the flanges being offset at its lower end, as shown at 16 so that the flanges will lap when the hod is folded as hereinafter explained and as illustrated in Figure 5.

A foldable end-board is provided between the side-board 8 and consists of segmental sections 17 hingedly connected along their inner or meeting edges as indicated at 18, the hinge being so located that these segments can fold inwardly between the side-boards. Additional hinges 19 connect the outer sides of the segments 17 with the respective side-boards and when the segments 17 are aligned, as shown in Figures 2 and 3, they bear outwardly against the stop flanges 15. For sealing purposes strips 20 of soft material such as rubber can be seated in the segments 17 so as to press against the top flanges as shown particularly in Figure 6.

A forked plate 21 is secured to the outer side of each side-board 8, each plate being extended upwardly from a jaw 22 which extends under the adjacent flange 3. From the jaws are extended stem sections 23 and 24 which, when brought together, form a substantially cylindrical screw-threaded stem. Two sections may be brought together along obliquely disposed faces 25, as shown, or could be otherwise shaped.

The hod handle is of the usual size and shape and has been indicated at 26. This handle has an interiorly screw-threaded sleeve 27 secured to one end and the sleeve is so proportioned that

when the stem sections 23 and 24 are pressed together, the sleeve can be screwed onto them so as to hold them together. When the stem sections are thus secured, the strips 1 and 2 are maintained with their surfaces 4 in alinement, with the side-boards 8 diverging upwardly, and with the segments 17 positioned at right angles to the side-boards and in alinement with each other. This will be plainly apparent by referring to Figure 4.

A shoulder rest or pad in the form of a block 28 is hingedly connected, as at 29, to one of the flanges 3 and is so positioned that when the flanges are pressed together as shown in Figures 2 and 4, this block can be extended under both flanges and can be secured detachably in proper position by means of a spring catch 29' engaging rib 30 on the other flange 3 as shown in Figure 2. When the block is thus positioned, it will operate to hold the flanges together until the sleeve 27 has been screwed onto the split stem made up of the parts 23 and 24.

When the hod is not in use the two segments 17 are folded together between the side-boards 8 and said side-boards are swung toward each other as shown in Figure 5. At this time the strips 1 and 2 are disposed along diverging lines with the stem sections 23 and 24 likewise diverging as shown in Figure 5. Thus the hod can be made into a compact bundle and can be conveniently carried from place to place in a conveyance.

When it is desired to set up the hod for use, the sections 23 and 24 are swung toward each other and the segments 17 are likewise swung outwardly so as to press against the sealing strips 20 and come into alinement with each other. The block 28 is then snapped into the position shown in Figure 2 so as to hold the flanges 3 in contact in a preliminary locking arrangement, and thereafter the sleeve 27 is screwed onto the contacting stem sections 23 and 24, thereby securely holding the parts of the hod assembled in position to carry a load. By providing the backing strips 5 and 20 it is possible to use the hod not only for carrying bricks and other solids but also for carrying mortar and other semifluid material.

It will be noted that the structure is very simple and compact and will not readily get out of order.

It is to be further noted that the weight of the load in the hod, pressing outwardly against the sectional end board, itself assists in making more

tight the sealing engagement between the end board and stop flanges. Further, any tendency of the load to press outwardly against the side boards only results in bringing into tighter engagement the bottom strips carrying the sealing means 6.

What is claimed is:

A hod including hingedly connected bottom strips, wedge-shaped in cross section, normally contacting along their inner faces along a line drawn longitudinally through the center of the hod, and normally diverging upwardly along their outer sides, the upper faces thereof normally meeting along said center line whereby to form a flat bottom, there being opposed grooves formed in the inner faces and spaced from the upper faces, a sealing means mounted in one of the grooves and proportioned to be received in the opposite groove, depending flanges on the strips extending the length thereof and proportioned to normally engage each other along said center line, a shoulder rest hinged to one of the flanges, a catch means hinged to the shoulder rest, for locking engagement with the hinge, whereby to provide a preliminary lock for the bottom strips, side boards secured to the outer sides of the strips, reinforcing frames respectively connected to the inner sides of the respective side boards, and to the upper faces of the bottom strips, stop flanges at one end of the reinforcing frames, hingedly connected segmental end sections, constituting an end board, sealably engageable by the stop flanges, hinge connections between the respective end sections and side boards, jaws fixedly connected to the respective side boards and proportioned to lockingly embrace the depending flanges, stem sections rigid with the jaws and engageable with each other to form a sectional stem, a handle, and means carried by the handle adapted to removably connect the handle to the stem.
